UNITED STATES PATENT OFFICE.

HARRY LE B. GRAY, OF ROCHESTER, NEW YORK.

FIRE-EXTINGUISHING SYSTEM.

1,117,834.

Specification of Letters Patent. Patented Nov. 17, 1914.

Application filed September 14, 1912. Serial No. 720,837.

To all whom it may concern:

Be it known that I, HARRY LE B. GRAY, of Rochester, in the county of Monroe and State of New York, have invented certain new and useful Improvements in Fire-Extinguishing Systems; and I do hereby declare the following to be a full, clear, and exact description of the same, reference being had to the accompanying drawings, forming a part of this specification, and to the reference numerals marked thereon.

My invention has for its object to provide a novel arrangement of fire extinguishing apparatus of that class known as automatic sprinkler systems, and in connection therewith it consists of an arrangement of discharge heads and thermostatic controlling means disposed relatively thereto in a room or inclosure whereby a conflagration originating in one locality may be checked by the discharge of water simultaneously from the sprinkler head nearest to the fire and from other sprinkler heads at one or more sides of the point at which the conflagration commenced. To these and other ends the invention consists in certain improvements and combinations of parts all as will be hereinafter more fully described, the novel features being pointed out in the claims at the end of the specification.

In the drawings: Figure 1 is a sectional view of a room or inclosure showing in elevation an apparatus illustrating one embodiment of my invention; Fig. 2 is a vertical cross sectional view taken on the line 2^x—2^x of Fig. 1; Fig. 3 is a horizontal sectional view on the line 3^x—3^x of Fig. 1, the apparatus appearing in plan; Fig. 4 is a detail view showing one of the relief valves and the thermostatic mechanism for operating it; Fig. 5 is a detail sectional view, showing one part of the thermostatic switch; Fig. 6 is a diagrammatic illustration showing the arrangement of the valve operating electro-magnets and the thermostatic switch contact controlling them; and Fig. 7 is a diagrammatic view illustrating a modified arrangement for controlling each valve by any one of a plurality of electromagnets.

Similar reference numerals throughout the several figures indicate the same parts.

Apparatus embodying my invention, is adapted particularly to be used as a means of protecting goods or stock of more or less highly inflammable character, which must

necessarily be handled or stored in open and exposed places, as well as for use in the rooms where such goods are manufactured, such as in flour mills, paint factories, cotton mills and the like. For convenience in illustration and as a means of showing the practical application of the apparatus, I have shown it in a form adapted particularly to be used in a room where strips of inflammable material, undergoing treatment, are suspended in open loops in such a way that ignition at one point would be quickly imparted to successive loops as it is an arrangement of goods particularly conducive to the rapid spread of fire from one end of a long room or inclosure to the other. The walls of the room are shown in section and indicated at 1, the material therein used only for purposes of illustration being indicated by 2 and shown suspended in continuous loops from rails or hangers 3, supported at their ends on track pieces 4 suspended from the ceiling 5 of the room by hangers 6.

The sprinkler system comprises a plurality of horizontally disposed cross pipes A, B, C, D and E, separated equi-distantly and extending across the ceiling of the room, having downwardly extending legs as indicated by A' and A'' in Fig. 2, which are disposed on each side wall of the room. The overhead cross pipes are provided with a plurality of discharge heads a, b, c, d, e discharging downwardly, and the side pipes A', A'' have similar heads a', a'' discharging inwardly, the arrangement of all of said heads being such that when water or other fluid is discharged therefrom, a complete water curtain or veil is formed dividing the room or inclosure into two, three or more distinctly separated sections, according to the number of cross pipes to which water may be supplied. Any convenient arrangement of piping may be employed as will be understood, but for purposes of illustration, I have shown the several cross pipes A, B, etc., connected by the respective pipes A'', B'', C'', D'' and E'' with a larger main 7, connected with any suitable source of water supply. In each of the pipes A'', B'', etc., preferably in proximity to the cross pipes provided with the discharge heads, there is arranged a suitable self-releasing valve mechanism which when tipped will automatically open by the pressure of the water in the pipes, permitting it to flow freely.

through the discharge heads. A valve suitable for this purpose, is shown in Fig. 4, having the valve stem 8, shown in dotted lines, which is forced inwardly into closed position and normally held in this position by a screw bolt 9, provided with the hand wheel 10. The bolt is separate from the valve stem and only engages the outer end of the latter and is carried in a yoke 11 pivoted at 12 to an arm 13 pivotally connected to the body of the valve at the point 14. The yoke 11 also carries the pivoted arm 15 and this arm carries a pivoted pawl 16 forming a toggle lever which normally engages a projection 17 extending from the body of the valve and so arranged that when the parts are in a position shown in Fig. 4, pressure on the valve head tending to move it away from its seat will be resisted through the various parts described, the yoke 11 being held closed and receiving the thrust on the bolt 9. The valve is tipped by dislodging the pawl 16 from engagement with the projection 17, a means for accomplishing this, being preferably the releasing lever 18 pivoted at 19 and adapted when moved in one direction to engage a projecting edge of the arm 15. These automatic release valves are each controlled by an electro-magnetic device in the form of a solenoid $a^a b^b$, etc., and each of said solenoids is arranged in a circuit which may be closed at any one of a plurality of points, by means of thermostatic devices disposed with relation to the character of the goods being operated upon in the enclosure or stored therein for the purpose of affording the greater protection. In the present arrangement I have shown the thermostat located above the goods 2, but these may be located in the room wherever found most desirable.

While I have described an embodiment wherein the actuation of any one thermostat operates all the valves, I prefer to adapt the system so that each thermostat controls the valves within a certain radius of the point of the fire, each valve being, at once, under the control of several thermostats. Fig. 7 shows an arrangement of this sort, in which K , K' , K^2 , etc., designate the thermostats, and M , M' , etc., N , N' , etc., and O , O' , etc., are the electromagnets for operating the valves, and arranged in the thermostat circuits as shown. With this construction if thermostat K is actuated the electromagnets M' , N^2 , O^2 will be operated to open the corresponding valves, and causing the respective veils of water to be discharged. The valves and discharge pipes may be arranged so that each thermostat will control double veils on two sides of the origin of the fire, or on all sides, forming a complete inclosing wall of water within which the fire may be confined. Each valve is adapted

to be operated by several thermostats, so as to variously combine the different veils of water, according to the position of the fire. Thus, if the thermostat K' is actuated, the electromagnets M' , N' , O^2 , P^3 , will be operated and the corresponding valves opened. 76

It will be understood that I do not limit myself to the precise arrangement shown, as I intend to cover by this application any modifications that may come within the scope of my invention and of the claims hereinafter. 78

Any suitable form of thermostatic mechanism may be used and in Fig. 5, I have shown an arrangement of parts which in actual practice has proven most satisfactory. This device comprises a pair of contacts 20 and 21, made of suitable spring material insulated from each other and mounted upon a finger or support 22 in a box 23, the face of which is provided with an aperture 24 covered with an inflammable substance, such as celluloid, indicated by 25. Where it is desired to make the thermostat very quick in its operation, the contact springs may be separated by a spacing member 26 of highly inflammable material, such as guncotton. If desired, one of the springs may be retracted and held in this position by a thread or link 27 of fusible material 95 which will give way and permit the contact springs to come together when a predetermined temperature corresponding to the melting point of the link is reached. 90

In the operation of my apparatus, assuming that the several valves are closed and that a fire originates around the discharge head d . Under such conditions, the valves controlling each of the pipes C , D and E will be automatically opened causing the veils of water to be discharged on opposite sides of the fire. In the same manner, if the fire is started at a discharge head b , the veils or pipes A , B and C will be discharged. The operation of any single thermostat will 110 open the corresponding series of valves, operating to effect a complete discharge of water at opposite points relatively to the fire origin, and thus confine the flames within an area surrounded by water. 115

I claim as my invention:

1. In a fire extinguishing system, the combination with a plurality of sprinkling pipes, of a valve for each pipe, locking means for each valve having cooperative engagement therewith to hold it normally closed, a plurality of electromagnets each of which has a connection with a locking means and adapted to release the same, each of said electromagnets being included in an independent circuit, and a thermostat common to all of said circuits. 120

2. In a fire extinguishing system, the combination with a plurality of sprinkling pipes, of a valve for each pipe, locking 125

means for each valve having co-operative engagement therewith to hold it normally closed, a plurality of electromagnets each of which has connection with a locking means and adapted to release the same, a plurality of circuits each of which includes several electromagnets controlling a plurality of valves, and a thermostat included in each circuit.

10 3. In a fire extinguishing system, the combination with a plurality of sprinkling pipes, each adapted to form a water veil when discharged, of a valve controlling each

pipe and a plurality of thermostats, each of said thermostats being operatively associated in common with a plurality of valves and controlling the latter and each located intermediate the pipes controlled thereby, whereby a series of veils of water may be discharged simultaneously at opposite points with relation to the controlling thermostat.
